C. L. BAKER,
TOP NOTCH AND RUNNER,
APPLICATION FILED SEPT. 28, 1921.

1,429,828.

Patented Sept. 19, 1922.

UNITED STATES PATENT OFFICE.

CHARLES L. BAKER, OF LANCASTER, PENNSYLVANIA.

TOP NOTCH AND RUNNER.

Application filed September 28, 1921. Serial No. 503,723.

To all whom it may concern:

Be it known that I, CHARLES L. BAKER, a citizen of the United States, residing at Lancaster, in the county of Lancaster and State of Pennsylvania, have invented certain new and useful Improvements in Top Notches and Runners, of which the following is a specification.

This invention pertains to rib-joint devices for umbrellas and parasols.

Heretofore it has been customary to make umbrella top-notches and runners of a construction adapted to receive ribs and stretchers having either pivot-eye or ball ends. The particular purpose of the present invention is to provide a top-notch or runner intended to receive either all pivot-eye or all ball-end ribs or stretchers, or if desired, one or more of the pivot-eye type may be used with the ball-end type, or vice versa. The great advantage of this combination construction will readily be seen, as with it, should an umbrella rib or stretcher be broken and another of the type used in the umbrella be not available, the umbrella can readily be repaired by the insertion of a rib or stretcher of the other type.

In the accompanying drawing which represents a practical embodiment of the invention, and wherein like reference numerals indicate like parts throughout the several views,

Figure 1 represents a side elevation of an umbrella top-notch embodying my invention in its preferred form;

Fig. 2, a similar view illustrating its application to the runner;

Fig. 3, a horizontal view of the top notch shown in Fig. 1 with a portion thereof broken away for clearness;

Fig. 4, a partial vertical section of the construction shown in Fig. 1;

Fig. 5, a partial vertical section of the construction shown in Fig. 2;

Fig. 6, the same view as Fig. 4, the umbrella ribs and the pivot-wire being omitted for clearness;

Fig. 7, a horizontal section taken on line 7-7 of Fig. 6;

Fig. 8, the same view as Fig. 5, the umbrella stretchers and the pivot-wire being omitted for clearness;

Fig. 9, a horizontal section taken on line 9-9 of Fig. 8; and

Fig. 10, a perspective of a ball-end umbrella rib or stretcher.

In the drawings, Figs. 1, 3, 4, 6 and 7 show the invention applied to the top-notch of an umbrella. The umbrella stick is represented at 1, the top-notch or main notch ring 2 being rigidly secured thereon by means of the usual pin 3 which passes through suitable holes provided in the stick and ring for this purpose. Top-notch or notch ring 2 is formed at its lower portion with a series of radial rib-receiving slots 4 corresponding in number to the ribs used in the umbrella. For sake of clearness, certain of the ribs are omitted from the drawing, only two of the ball-end type and one of the pivot-eye type being shown. The pivot-eye rib is indicated by 5, and is provided with the usual flattened end 5^a. An annular groove or slot 6 is provided in the upper portion of top-notch 2 and serves to connect the several vertical slots 4. Annular slot 6 is intended to receive the usual pivot-wire 7, one end thereof being passed through the pivot-eye 8 of rib 5 and secured to its opposite end at 9 so as to pivotally support the upper end of rib 5 within its corresponding vertical slot 4. Should additional pivot-eye ribs be used, they would be secured in place in the same manner.

A portion of a ball-end rib or stretcher is shown in Fig. 10. In order to receive this type of rib, socket recesses are formed in top-notch 2 in connection with vertical slots 4. Vertical slots 4 and annular slot 6 form a series of radial partitions or lugs 10 on top-notch 2. In the opposing vertical faces of these partitions 10 facing on slots 4, there are provided elongated recesses 11 extending from the upper edges of partitions 10 to within a short distance of their lower edges, the lower ends of the recesses being rounded as indicated at 12.

Slots 4 and annular slot 6 also form a second series of radial partitions or lugs 13 overlying and corresponding to lugs 10. The side faces of lugs 13 facing on slots 4 are provided with rounded recesses 14 in vertical alignment with recesses 11 of lugs 10. Thus it will be seen that recesses 14 afford enlarged passageways in conjunction with vertical slots 4 whereby the ball ends 15 of ribs 16 may be inserted from above into the sockets formed by recesses 11 in the oppos-

ing walls of lugs 10. The ball-end ribs having been placed in position in their sockets first, the pivot-eye rib or ribs are secured in slots 4 of top-notch 2 by means of pivot-wire 7 as heretofore explained. In addition to securing the ends of the pivot-eye ribs in place, pivot-wire 7, it will be seen, prevents the upward movement of the ball-end ribs out of their sockets. The flattened portions 10 5^a and 17 at the upper ends of pivot-eye and ball-end ribs 5 and 16 respectively, allow free pivotal movement of the ribs in slots 4 without interference from lugs 10 and 13. The invention is equally as applicable to 15 the runner or lower notch-ring as shown in Figs. 2, 5, 8 and 9 of the drawing. The runner sleeve 18 mounted on stick 1 is provided with the usual slot 19 for the passage of the spring-catch 20. Runner sleeve 18 20 is provided intermediate its ends with an annular rib 21. Runner ring or notch-ring 22 is mounted on the upper end of sleeve 18 and rests on rib 21, while upward movement of the ring thereon is prevented by an 25 annular flange 23 formed on the upper end of sleeve 18.

Runner ring 22 is practically the same as top-notch 2 except that it is inverted. Ring 22 is provided with a series of radial vertical slots 24 corresponding to slots 4 of top-notch 2, and an annular slot 25 joining slots 24 and corresponding to slot 6 of top-notch 2. The side faces of the upper series of lugs 26, the latter being formed by slots 24 30 and annular slot 25, are provided with recesses 27 similar to those formed in lugs 10 of the top-notch 2. A second series of lugs 28, underlying and corresponding to lugs 26, are formed on the runner ring 22 by 35 vertical slots 24 and annular slot 25. The side faces of lugs 28 facing on slots 24 are provided with recesses 29 corresponding to those in lugs 13 of the top-notch 2.

With the runner construction described, 40 it will be seen that stretchers, either of the pivot-eye type or the ball-end type or the two types together may readily be secured in the runner by means of pivot-wire 7 in the same manner as the ribs are secured in 45 the top-notch 2.

It is intended that the terms "rib" and "stretcher" shall be regarded as synonymous wherever they appear in the description or in the appended claims. The same 50 also applies to the terms "top-notch," "runner" and "notch ring."

Although a practical embodiment of the invention has been shown and described, it is contemplated that the detail constructions

may be modified without departing from the 60 invention, except as the same is limited by the appended claims.

Claims:

1. A rib-joint device for umbrellas having means for pivotally securing thereto 65 pivot-eye and ball-end ribs.

2. A rib-joint device for umbrellas having combination socket-and-slot recesses therein to receive pivot-eye and ball-end ribs and means for securing said ribs in place. 70

3. A rib-joint device for umbrellas having combination socket-and-slot recesses therein for either pivot-eye or ball-end ribs, said recesses being connected by an annular slot, and a pivot wire secured in said slot to hold 75 said ribs in place.

4. A rib-joint device comprising a notch-ring having a series of regularly-spaced vertical rib-receiving slots and an annular pivot-wire slot connecting said rib-receiving 80 slots, whereby an upper and a lower series of radially projecting lugs are formed on said ring, the opposed faces of said lower series of lugs facing on said rib-receiving slots being provided with recesses forming 85 rib-receiving sockets opening into said pivot-wire slot.

5. A rib-joint device comprising a notch-ring having a series of regularly-spaced vertical rib-receiving slots and an annular 90 pivot-wire slot connecting said rib-receiving slots, whereby an upper and a lower series of radially projecting lugs are formed on said ring, said lower series of lugs being provided with rib-receiving sockets opening 95 into said pivot-wire slot, and a pivot-wire for securing ribs in said vertical slots, said wire, when in place, serving to partially close the upper ends of said rib-receiving sockets.

6. A rib-joint device comprising a notch-ring having a series of regularly-spaced vertical rib-receiving slots and an annular pivot-wire slot connecting said rib-receiving 100 slots, whereby an upper and a lower series of radially projecting lugs are formed on said ring, the opposed faces of said lower series of lugs facing on said rib-receiving slots being provided with recesses forming rib-receiving sockets opening into said pivot-wire slot, and the opposed faces of said 105 upper series of lugs facing on said rib-receiving slots being recessed to permit the insertion of ball-end ribs into said rib-receiving sockets.

In testimony whereof I have signed my 110 name to this specification.

CHARLES L. BAKER.
